UNITED STATES PATENT OFFICE

114,648

DESIGN FOR A TELLURIAN

Otto A. Schumann, Houston, Tex.

Application January 6, 1939, Serial No. 82,207

Term of patent 14 years

To all whom it may concern:

Be it known that I, Otto A. Schumann, a citizen of the United States, residing at Houston, in the county of Harris and State of Texas, have invented a new, original, and ornamental Design for Tellurians, of which the following is a specification, reference being had to the accompanying drawing, forming part thereof.

The figure is a perspective view of a tellurian, showing my new design.

I claim:

The ornamental design for a tellurian, as shown.

OTTO A. SCHUMANN.
